UNITED STATES PATENT OFFICE

SAMUEL L. HALL, OF BELLEFONTAINE, OHIO

WEEDER TOOTH AND MOUNT

Application filed October 17, 1930. Serial No. 489,419.

The invention relates to weeder teeth and mounts particularly adapted for use in the cultivation of corn without plowing, and particularly for working clay soil after it has been come crusted.

A further object is to mount the tooth on a spring arm having a loop for increasing the range of flexibility of the arm and to provide means whereby the double pointed tooth may be easily and quickly removed for sharpening purposes or reversed for using either sharpened end thereof.

A further object is to provide a tooth which may be easily sharpened, will not become bevelled or blunt, as is now the difficulty with weeder teeth as at present constructed where the body of the tooth is relatively heavy, and one which may be formed from a relatively hard metal, and as a separate part from the arm, thereby allowing the arm to be formed from a softer and cheaper metal.

A further object is to provide the lower end of the spring arm with a sleeve having an apertured boss, through which the double ended tooth extends and a set screw carried by the boss and cooperating with the tooth for holding the same in various adjusted positions.

A further object is to provide the upper end of the spring arm with a horizontal arm extending through an aperture in the downwardly extending flange of the angle bar of the machine, and terminating in a U-shaped member engaging the under side of the horizontal flange of the angle bar and held by a plate bolted to the under side of the horizontal flange and having a portion arching the transverse portion of the U-shaped member.

A further object is to provide the portion of the plate, which arches the transverse portion of the U-shaped member with an upwardly extending flange, engaging the forward edge of the horizontal flange of the an-

gle bar for holding the plate against pivotal movement on its single bolt.

A further object is to dispose the arms of the U-shaped portion of the horizontal portion of the spring arm in engagement with opposite sides of the plate for preventing pivotal movement in a horizontal plane of the spring arms in the aperture of the downwardly extending flange.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a perspective view of the tooth and spring arm.

Figure 2 is a vertical transverse sectional view through the angle bar of the spring arm mounting.

Figure 3 is a bottom plan view of the angle bar showing the spring arm mounting.

Figure 4 is a vertical longitudinal sectional view through the tooth mounting.

Referring to the drawings, the numeral 1 designates the horizontal angle bar of a conventional form of weeder, 2 the horizontal flange thereof and 3 the downwardly extending flange.

In weeder teeth heretofore constructed, the teeth have been formed as an integral portion of the tooth arm and the arms have been formed from flat material, however it has been found that the teeth soon become blunt on their forward edges and will not penetrate hard surfaces, such for instance as the crust formed on clay soil. To form the teeth from material which will not easily wear would be an expensive operation, as it would be necessary to form the entire tooth arm from high grade expensive steel.

The spring arm 4 is formed from spring rod material and terminates in a horizontal arm 5 at its upper end having a loop 6, which allows a relatively wide range of flexibility to the arm, the purpose of which will presently appear.

Threaded at 7 on the lower end of the spring arm 4 is a sleeve 8, which sleeve has its rear side provided with an integral boss 9, having an aperture 10 extending vertically therethrough, and through which the hard steel tooth 11 extends and is held by means of the set screw 12. It will be seen that by manipulating the set screw, the tooth 11 may be adjusted upwardly or downwardly in relation to the ground or reversed, or when desired, removed for resharpening purposes. The ends of the hard steel point 11 are sharpened as shown at 13, and as the point 11 is of relatively small diameter, it is obvious the points will easily pierce the ground and when they hit an obstruction, the spring arms 4 will flex, allowing the points to pass over the obstruction but to be immediately forced into the ground through the hard crusts after passing the obstruction, which is not possible with weeder teeth as at present constructed which will not pierce the hard crust of clay soil. It will be noted by making the teeth 11 removable, when it is desired to sharpen the teeth they may be easily removed without removing the entire arm from the weeder, therefore the present device overcomes another objection to weeder teeth as at present constructed.

The forward end of the arm 5 extends through an enlarged aperture 14 in the downwardly extending flange of the angle bar 1 and terminates in a U-shaped portion 15 having its transverse portion 16 with its forward side 17 in registration with the forward edge 18 of the flange 2 of the bar, so that the upwardly extending flange 19 of the clamping plate 20 will engage the arm 16 and the edge 18 of the bar flange for preventing movement of plate 20 on bolt 21.

It will be noted that arm 5 engages one side of the clamping plate 20 and the arm 22 of the U-shaped member engages the opposite side of the plate 20, therefore it will be seen that in combination with the single securing bolt 21, the arm 5 is rigidly anchored by a single clamping plate and bolt, thereby reducing the cost of manufacture to a minimum and simplifying the anchoring of the spring arm.

From the above it will be seen that a weeder tooth and mounting is provided, which is simple in construction, may be easily reversed or removed for resharpening or changing the point, and a weeder tooth is provided which will easily and positively puncture hard crusts formed on hard clay soil, thereby allowing cultivation of corn and other plants.

The invention having been set forth what is claimed as new and useful is:—

The combination with a spring weeder arm, a member carried by the lower end of said arm, of a boss rearwardly of said member, a tooth extending through said boss, the ends of said tooth being sharpened, said tooth being reversible in said boss and a set screw carried by the boss and holding the tooth in the boss.

In testimony whereof he hereunto affixes his signature.

SAMUEL L. HALL.
